UNITED STATES PATENT OFFICE.

KARL KÜPPERS, OF AACHEN, GERMANY.

INCANDESCENT GAS-BURNER.

No. 918,753.

Specification of Letters Patent. Patented April 20, 1909.

Application filed October 3, 1906. Serial No. 337,290.

To all whom it may concern:

Be it known that I, KARL KÜPPERS, a subject of the King of Prussia, German Emperor, and resident of 27-29 Stefanstrasse, 5 Aachen, in the Province of the Rhine, German Empire, engineer, have invented new and useful Improvements in Incandescent Gas-Burners, of which the following is an exact specification.

10 My invention relates to incandescent gas burners of the type in which a quantity of pure gas is joined with a quantity of gas and air mixture for the purpose of economically producing a flame of higher temperature.

15 Such a burner is described in my prior U. S. Patent No. 802,297, dated October 17th, 1905.

The object of the present invention is to effect a still greater economy in burners of 20 this type and this greater economy is effected by pre-heating the gas of the pure gas flame. The arrangement used may also be adapted to effect a pre-heating of the mixture, so that the pure gas as well as the mixture of gas and 25 air passes to the burner in a heated state. Burner constructions of this kind can be used for common upright incandescent gas-lights as well as for those of the inverted type.

In order to make my invention better understood I accompany same by drawings in which:

Figure 1 represents a constructional form for pre-heating gas alone, showing the arrangement in a vertical section. Fig. 2 is a 35 cross section on line A—B of Fig. 1. Fig. 3 a cross section on line C—D of Fig. 1 and Fig. 4 resembles a modified arrangement of the pre-heating device in a vertical section, in which the mixture of gas and air is also 40 pre-heated.

a is the inner tube through which gas flows coming from the gas conduit not further shown in the drawing.

g is a body of insulating material to which 45 the inner tube *a* and the tube *c* are attached, and which forms a chamber *g'*.

d is an outer tube closed at its upper end and surrounding the tube *c*.

e' is a tapered part in connection with the 50 lower end of the tube *d* and provided with perforations *e*.

*e*² is an enlarged short tube forming the continuation of the tapered part *e'* and fitting into the chamber or recess *g'* of the insulated body. The latter can be provided with projections or ribs of heat-conducting

material for increasing the preheating action of the arrangement. Furthermore the tube *d* can be provided with an enlargement and fitted with an insulating mantle in its lower 60 end.

h is an outer tube surrounding the inner tube *a* and the body *g*. At its lower end the tube *h* is connected with the inner tube *a* by the flange *b'* having openings *b* through which 65 the gas can enter the annular space formed by the tubes *a* and *h*.

k is a perforated body such for instance as a sieve which together with the perforated part *e'* forms the burner head. The funnel-shaped perforated tube part *k* of the burner head is attached at its lower end to the piece *g* and bears with its upper end against the tube *h*.

l is a covering or plate carried by the upper 75 end of the outer tube *h* and provided with openings or perforations *n* and with slots *m*. At the lower end or near it a number of holes *i* are cut into the tube *h*, through which fresh air enters from the outside and admixes with 80 the gas within the tube *h*. This arrangement as foregoing described operates in the following manner:—The gas flows partially through the openings *b* and enters partially the inner tube *a*. That gas, which passes the opening 85 *b*, mixes in the annular space formed by the tubes *a* and *h* with air and discharges at the top of the tube *h* through the openings and slots *n* and *m* respectively, after having passed the sieve *k*. The part of the gas entering the 90 tube *a* flows upward through the tube *c* and then downward through the annular space formed by the tubes *c* and *d*. In passing through the space the gas becomes intensely pre-heated on account of the outer tube *d* 95 being surrounded by the lamp flame, which pre-heated gas finally enters the chamber *g'* and from there passes through a number of small openings *e* in the tapered part *e'*, where it admixes with the gas and air mixture, 100 which immediately afterward rushes through holes *n* and slots *m* into the flame.

In the Fig. 4 a modified arrangement of the preheating device is illustrated. According to this figure the outer tube *d* is dispensed 105 with and a tube *a'* closed at its upper end, is provided within the chamber *g'* with openings or perforations *b*². The tapered part *e'* of the mantle *e*² is attached to the tube *a'* and provided with openings *e*. By means of this 110 arrangement the heat is conducted from the upper part of the tube *a'* to its lower portions

and in this way the gas passing through this lower portion of the tube a' is pre-heated by the time it passes through the openings b^2 . The mixtures of gas and air which have 5 around the hot walls of the lower portions of tube a will in this construction be also pre-heated to a certain extent before it reaches the burner head.

Having thus fully described the nature of 10 my said invention, what I desire to secure by Letters Patent of the United States is:—

1. In an incandescent burner, a burner head, a gas supply pipe, a conduit communicating directly with the atmosphere and with 15 the supply pipe and leading to said burner head, a second conduit closed to the atmosphere leading from the gas supply pipe to the burner head and means for heating portions of said second conduit.

2. In an incandescent burner, a burner head, a gas supply pipe, a conduit communicating directly with the atmosphere and with the supply pipe and leading to said burner

head, a second conduit closed to the atmosphere leading from the gas supply pipe to the 20 burner head and means for heating both of said conduits.

3. An incandescent gas burner having a burner tube with perforations opening to the atmosphere, a gas supply pipe leading to said burner tube, a concentrically arranged pipe within the burner tube and leading from said gas supply pipe and for part of its length within the flame, a burner head comprising a perforated plate, through which the mixture of gas and air passes and a perforated outlet plate through which the pure gas from said concentrically arranged pipe passes, substantially as described and for the purpose set forth.

In witness whereof I have hereunto set my hand in the presence of two witnesses.

KARL KÜPPERS.
